UNITED STATES PATENT OFFICE.

HOWARD EARL HOOVER, OF CHICAGO, ILLINOIS, ASSIGNOR TO THE HOOVER SUCTION SWEeper COMPANY, OF NEW BERLIN, OHIO, A CORPORATION OF OHIO.

SUCTION-SWEeper.

1,334,757.

Specification of Letter Patent. Patented Mar. 23, 1920.

Application filed March 11, 1918. Serial No. 221,627.

To all whom it may concern:

Be it known that I, HOWARD EARL HOOVER, a citizen of the United States, residing at Chicago, in the county of Cook and State of Illinois, have invented a certain new and useful Improvement in Suction-Sweepers, of which the following is a specification.

My invention relates to improvements in suction nozzles for suction sweepers and has for one object to provide a supporting means for an end removable brush within the nozzle. Another object is to provide means for adjusting the height of the brush as the bristles wear to keep the bristle ends in the proper operative relation with the floor or the surface covering to be cleaned. Another object is to provide means for automatically and properly adjusting the two ends of the brush simultaneously. Another object is to provide a suction nozzle wherein fixed brush finger guards may be provided and wherein the brush itself may be withdrawn without interfering with said finger guards. Another object is to provide a brush which may be adjusted toward and from the surface to be cleaned without removing it from its operative position within the suction nozzle. Another object is to provide individual guard fingers capable of individual separate replacement. Other objects will appear from time to time in the specification.

My invention is illustrated, more or less diagrammatically in the accompanying drawings, wherein—

Figure 1 is a side elevation of the end of the suction nozzle with the suction sweeper itself broken away;

Fig. 2 is a section along the line 2—2 of Fig. 1;

Fig. 3 is a section along the line 3—3 of Fig. 2 looking in the direction of the arrows with brush removed and

Fig. 4 is a section along the line 4—4 of Fig. 3.

Like parts are indicated by like characters in all the figures.

A is the suction sweeper housing. It normally forms a part of an assembly which contains the usual motor and suction fan and transmission from the motor to the beating and sweeping brush. These features form no part of my present invention and I have, therefore, omitted them. The open mouth suction nozzle at A¹ located on the under side of the housing A is bounded by front

and rear walls A², A³ and is barred off by spring finger guards A⁴. These guards pass through perforations A⁵ in the lower edge of the front wall A² which wall is reinforced as indicated to provide a bearing for these 60 fingers. The fingers are bent to engage slots A⁶ which hold them against rotation and they are held in position by nuts A⁷. The rearward ends of the fingers are bent upwardly and rearwardly as at A⁸ to overhang 65 a flange A⁹ projecting forwardly into the nozzle from the rear wall A³ as indicated. These finger guards can, of course, be removed by a mechanic but they are for all practical purposes immovable and permanent. The user of the machine will ordinarily not take out the fingers. When necessary they can be removed by a repair man or by any ordinary skilled mechanic and they may be replaced without difficulty by such 70 man when they wear out or break or bend. In a very real sense, however, these fingers are fixed because the operator of the machine will never have occasion to remove these fingers and would ordinarily not be able so to 75 do so that for all practical purposes they are fixed permanent fingers.

The nozzle is provided with two absolutely identical end walls and I have shown and will describe therefore only one as a description of one will suffice for the other. The end wall is apertured as at B and this aperture is adapted to be closed by a circular disk B¹. The joint between the boundary of the aperture and the periphery of the 80 disk is rabbeted as indicated in order that the inward movement of the disk may be limited. B² is a spring locking finger pivoted on the screw B³ on the end wall and having a boss B⁴ adapted to engage a counter 85 sunk hole B⁵ in the disk B¹ and provided with ears B⁶ which may be engaged by the hand of the operator for the purpose of manipulation. B⁷ is a pin placed in the end wall of the nozzle adapted to be engaged by 90 a notch B⁸ in the disk or plate B¹ whereby the plate is held against rotation and must always be properly positioned before it can be seated.

C is a brush carrying and adjusting lever. 105 It is pivoted on a pin C¹ which penetrates a perforation C² in the plate B¹ and is rotatably mounted thereon. This lever is in general terms triangular in shape with its apex at the pin C¹. It has a curved cover- 110

ing portion C^3 substantially concentric with the pin C^1 carrying a rivet C^5 which passes outwardly through a curved slot C^6 in the plate B^1 and carries a thumb nut C^7 whereby 5 the lever may be manipulated and locked against rotation in position on the inner side of the plate B^1 . C^8 is a pointer carried by a washer C^9 on the bolt C^5 and provided with a squared portion as indicated to engage and 10 travel in the slot C^6 whereby the pointer is held always in proper relation to the indicating lines C^{10} on the outside of the plate B^1 thus enabling the operator at a glance to see just what adjustment has been made.

15 The central portion of the lever C is formed into a cup D having its base resting against the inner side of the plate B^1 and having its angular portion D^1 arranged to surround and overhang the beating brush D^2 which is flanged as at D^3 , the flange being located within but everywhere out of contact with the cup. Suitable means are provided for driving this brush not here indicated. D^4 is a shaft extending 20 from the bottom of the cup D on one side to a similar cup on the other side thus tying the parts together and furnishing a back bone for the brush. D^5 is a bearing sleeve within the brush rotatably mounted on the 25 shaft and D^6 are the brush bristles.

It will be noted that there is a free space 30 between the end of the brush and the bottom of the cup between the flange on the end of the brush and the walls of the cup so that any air which is introduced into the 35 cup at the end of the brush will be free to pass out around it to keep dust and dirt away from the brush end. The slot C^6 is open through the plate B^1 and communicates with an air passage E formed in the 40 portion C^3 of the lever C . This passage is of such length that it is always in register with the slot C^6 but the slot C^6 is never free to communicate directly with the interior of 45 the suction nozzle. E^1 is a passage communicating with the passage E and also with apertures E^2 through the bottom of the cup. Thus air is introduced in a stream into the 50 bottom of the cup through the slot C^6 and thus as long as there is suction in the nozzle this stream of air will pass in driving the dust and dirt away from the ends of the brush.

It will be evident that while I have shown 55 in my drawings an operative device, still many changes might be made both in size, shape and arrangement of parts without departing materially from the spirit of my invention and I wish, therefore, that my drawings be regarded as in a sense diagrammatic.

The use and operation of my invention are as follows:—

The nozzle is expected to be passed over 60 a carpet, rug or other floor covering to be

cleaned in the usual manner. A current of air is drawn in through the nozzle by means not here shown. The brush is rotated positively by the motor which operates the air current producing means. These features 70 form no part of my present invention and that is why they are not here shown. In order that the carpet may not be drawn up in the nozzle and wound about the brush, I provide a series of guard fingers extending 75 across the plane of the nozzle. These fingers also keep the carpet from being drawn tip too near to the center of rotation of the brush and thus reduce the pressure on the brush bristles and protect the brush against 80 too rapid wearing away. These fingers are made of preferably a very hard tempered steel because they are worn away from the back by the brush bristles and from the front by the carpet and if they are not hard they 85 will wear away with fatal rapidity or else bend by contact with the brush or the carpet. However, owing to their hardness they are more or less brittle and they do break. It sometimes becomes necessary to replace them 90 and means are provided as indicated whereby a mechanic can replace them. They are, however, for all practical purposes fixed in position. The operator who uses the machine is not expected to tamper with the fingers. They are separate and independent 95 and locked in position.

It is frequently necessary to change the brush or to adjust it or withdraw it for 100 cleaning or to replace the belt which drives it and I have provided means whereby the brush may be withdrawn through the end of the nozzle without interfering with the fingers. In order to withdraw the brush you swing the spring closure holding member to one side and pull out the closure. This brings with it the brush supporting and adjusting lever and leaves the brush free in the nozzle because the brush shaft just rests within a perforation in the bottom of the cup-shaped thread guard. The operator then moves the brush longitudinally out of the nozzle, the bristles bending sufficiently to pass through the aperture and the pulley being small enough to go through. 110 It is then possible to change the brush, to clean it, or to adjust or change the belt. In order to put the machine in operation again the brush may be returned in place by engaging the shaft with the socket in the bottom of each of the two cup-shaped thread guards by seating the closing disk or plate and throwing the spring plate holding lever into place.

With the two end closures in place the 125 brush may be moved toward and from the plane of the nozzle by loosening the thumbscrews and moving them up or down through the curved slot. The adjustment of height of the brush is arbitrarily indicated 130

by the indicator finger going with the thumb-screw. When the proper position is reached the screw is tightened and the brush is in position for operation.

5 The cleaning and protecting of the bearing at the end of the brush is provided by the cup-shaped thread guard and by a current of air which is drawn in through the end closure and through the body of the 10 thread guard. This air comes in through the slot in the closure through which the brush adjusting thumb screw projects. This air comes into a path or corridor just inside the periphery of the cup-shaped thread 15 guard and inclosed on one side by the plate thence the air passes in through perforations in the bottom of the cup-shaped thread guard in the space between the end of the brush and the thread guard whence it passes 20 around the end of the brush and is discharged from the thread guard into the body of the suction nozzle.

It will be noted, of course, that the pin arrangement for holding the end closure 25 against rotation is nothing more or less than a key and a key may be attached to the plate or it may be attached to the closure but there must be a keyway or key seat on whichever one of the two parts does not 30 carry the key for the purpose of insuring that the parts shall be properly positioned. This key, of course, might be put in as separate from the casting or it might merely be an ear or tooth or integral portion but it 35 acts as a key.

I claim:—

1. In a suction cleaner, a nozzle provided with a dust inlet opening and an end apertured wall, in combination with a brush 40 supported within the nozzle and adapted to be moved endwise through the aperture, a plate on which the brush is supported which serves as a closure for the end aperture, a lever pivoted on the plate, means for supporting the brush thereon and a cup-shaped 45 thread guard integral with the lever, surrounding the end of the brush and larger in cross section than the brush end, the plate and thread guard apertured and 50 shaped so as to provide an unobstructed air passage from outside the nozzle to and beyond the ends of the brush.

2. In a suction cleaner, a nozzle provided with a dust inlet opening and an end apertured wall, in combination with a brush 55 supported within the nozzle and adapted to be moved endwise through the aperture, a

plate on which the brush is supported which serves as a closure for the end aperture, a lever pivoted on the plate, means for supporting the brush thereon and a cup-shaped thread guard integral with the lever, surrounding the end of the brush and larger in cross section than the brush end, said brush end provided with a flange within 60 the cup, the plate and thread guard apertured and shaped so as to provide an unobstructed air passage from outside the nozzle to and beyond the ends of the brush.

3. In a suction cleaner, a nozzle provided with a dust inlet opening and an end apertured wall, in combination with a brush supported within the nozzle and adapted to be moved endwise through the aperture, a plate on which the brush is supported which 70 serves as a closure for the end aperture, a lever pivoted on the plate, means for supporting the brush thereon and a cup-shaped thread guard integral with the lever, surrounding the end of the brush and larger 75 in cross section than the brush end, said plate being slotted concentric with the lever and locking and adjusting means extending through said slot engaging the lever and means including said slot for introducing a 80 current of air from the outside into the suction nozzle around the end of the brush.

4. In a suction cleaner a nozzle provided with a dust inlet opening, a brush supported in the nozzle and means for rotating 90 it, a guard finger bent and screw-threaded at one end, the wall of the nozzle being slotted and perforated, the slot to engage the bent portion of the finger, the perforation to engage the screw-threaded portion and a 95 nut to engage the screw-threaded part of the finger to lock it in position.

5. In a suction cleaner a nozzle provided with a dust inlet opening, a brush rotatably mounted therein, a guard finger extending 100 across the open mouth of the nozzle, means for holding the guard finger in position in the nozzle comprising a slot within the wall of the nozzle, a bent extension of the guard finger and means for rigidly holding 105 such bent guard finger extension in place within the slot.

In testimony whereof I affix my signature in the presence of two witnesses this fifth day of March, 1918.

HOWARD EARL HOOVER.
